US00D766599S

(12) **United States Design Patent** (10) **Patent No.:** **US D766,599 S**
(45) **Date of Patent:** **** Sep. 20, 2016**

(54) **LOWER BODY GARMENT WITH INNER SURFACE ORNAMENTATION**

(71) Applicant: **Under Armour, Inc.**, Baltimore, MD (US)

(72) Inventors: **Kyle Sanders Blakely**, Baltimore, MD (US); **Peter Fong**, Vancouver (CA); **Julian McClain**, Baltimore, MD (US)

(73) Assignee: **Under Armour, Inc.**, Baltimore, MD (US)

(**) Term: **14 Years**

(21) Appl. No.: **29/490,383**

(22) Filed: **May 9, 2014**

Related U.S. Application Data

(62) Division of application No. 29/448,227, filed on Mar. 11, 2013, now Pat. No. Des. 704,455.

CLAIM

The ornamental design for a lower body garment with inner surface ornamentation, as shown and described.

DESCRIPTION

The sole FIGURE is a front view of a lower body garment with inner surface ornamentation showing our new design. The exterior of the article drawn in broken lines and the interior of the article that is not shown are not included in the claim. The broken lines immediately adjacent to the solid line areas in the drawing depict the boundaries of the claim and form no part thereof.
